UNITED STATES PATENT OFFICE.

MAXWELL VIDAVER, OF NEW YORK, N. Y.

APPARATUS FOR MANUFACTURING TOILET-PINS.

1,353,294.

Specification of Letters Patent. Patented Sept. 21, 1920.

Application filed August 1, 1919. Serial No. 314,603.

To all whom it may concern:

Be it known that I, MAXWELL VIDAVER, a citizen of the United States, and a resident of New York, in the county of New York and State of New York, have invented certain new and useful Improvements in Apparatus for Manufacturing Toilet-Pins, of which the following is a specification.

The present invention relates to improvements in an apparatus for manufacturing toilet-pins.

Toilet-pins usually comprise each a short, stiff piece of wire, with a sharp point and a round, substantially spherical head, the latter being made of vitreous or similar material. In manufacturing these pins, wire is first cut into pieces of the required length, the blanks so formed being then pointed and thereafter the blunt ends of the pins 20 dipped into a vitreous mass to produce the heads. The finished product is then usually mounted upon card-board cubes, into each face of the cube being stuck a predetermined number of pins, so that only their heads are 25 visible.

The main object of the present invention is to provide a simple and inexpensive apparatus, by means of which the pointed pin blanks are evenly distributed in spaced relation upon and clamped to a frame, preparatory to their blunt ends being dipped to form heads thereon, said frame serving also to mount the pins on the paste-board cubes, as above specified.

With these and other objects in view, which will more fully appear as the nature of the invention is better understood, the same consists in the combination, arrangement and construction of parts hereinafter 30 described, pointed out in the appended claims and illustrated in the accompanying drawings, it being understood that many changes may be made in the size and proportion of the several parts and details 40 of construction within the scope of the appended claims without departing from the spirit or sacrificing any of the advantages of the invention.

One of the many possible embodiments 50 of the invention is illustrated in the accompanying drawings, in which:

Figure 1 is a top plan view, partly in

section, of an apparatus constructed in accordance with the present invention; Fig. 2 is a front elevation thereof, partly in section, on a larger scale; Fig. 3 is an end view of the same; Fig. 4 is a section taken on line 4—4 of Fig. 2; Fig. 5 is a top plan view, partly in section, of one of the clamping frames of the apparatus; Fig. 6 is a 60 diagram showing the method of mounting the finished pins on a paste-board cube; and Fig. 7 is a perspective view of a cube with the pins mounted thereon.

In the drawings, the numeral 10 indicates 65 a base-plate, from which rise side frame sections 11. In these frame sections are formed registering, vertically extending slots 12, through which extend lugs 13 on a hopper 14. This hopper is made in the 70 form of an oblong receptacle, which is divided by a plurality of longitudinal partitions 15 and transverse partitions 16 into a number of compartments. In the case 75 illustrated in the drawings, there are eight compartments in each transverse row, lengthwise in each row there being a multiple of eight, for a purpose which will hereinafter appear. The bottom 17 of the hopper is of a substantial thickness, and is 80 provided with apertures 18, each of which is of a diameter that is somewhat larger than the pin blanks to be distributed. Within each compartment of the hopper there are formed in the said bottom four 85 apertures, the entire number of apertures in said bottom being distributed substantially equidistantly, and disposed in rows that extend both lengthwise and also transversely of the hopper, that is to say parallel 90 to the longitudinal partitions and also to the transverse partitions above mentioned.

The hopper is given a reciprocating or vibrating movement by a suitable mechanism, including in the present case bars 19, 95 fixedly attached to the lugs 13, said bars extending vertically through guides 20, and coöoperating each with a star-wheel 21. These wheels are rigidly secured to a horizontally extending shaft 22, that is rotatably mounted in bearings on the side frames 11 and provided with a crank 23. The slots 12, in coöperation with the lugs 13, serve as guides for the hopper, which receives, by

turning the crank 23 in the direction of the arrow shown in Fig. 3 of the drawings, a quick vibrating or reciprocating movement, for a purpose which will be described hereinafter. Springs 14', attached to the hopper and guides 20, serve to hold the bars 19 in engagement with the star-wheels.

A substantial distance below the hopper there is formed upon the inner face of each side frame a horizontal ledge 24, said ledges being adapted to support a plate member 25, upon which are adapted to rest clamping frames 26. The plate member 25, when on the said ledges, abuts against stops 27, mounted upon the rear faces of the side frames, said stops projecting inwardly, as clearly shown in Fig. 1 of the drawings. In alinement with these stops the rear longitudinal edge of the plate member 25 is provided with an upwardly extending flange 28, against which the frames 26 are adapted to abut. The frames extend each throughout the width of the hopper 14, and are square in configuration, as appears from the drawings. When upon the plate member 25, the frames 26 are properly spaced apart by transverse ridges 29, that project downward from the underface of the hopper bottom.

Each of the clamping frames 26 comprises two side walls 30 and two end walls 31, said end walls being connected by tie-bars 32, disposed parallel to the side walls 30. To these tie-bars are fixed the stationary jaws 33 of the clamping frame, said jaws being made each in the form of a strip and extending all in parallel relation to the end walls 31 of the clamping frame throughout the length thereof. With each stationary jaw co-operates a movable jaw 34, also in the form of a strip, said movable jaws being slidably mounted upon the tie-bars. For simultaneously actuating the movable jaws, there are two screw-threaded spindles 35 rotatably mounted in the end walls 31 of the clamping frame, said spindles passing through screw-threaded holes 36 in the movable jaws and through holes 37 in the stationary jaws. The holes 37 are each of a diameter that is larger than the diameter of a spindle 35.

The stationary jaws of the clamping frames are substantially in alinement with the longitudinal partitions 15 in the hopper, so that pins passing through the apertures 18 in the hopper bottom abut against the said stationary jaws, to be clamped thereagainst by the movable jaws, when the latter are moved toward the stationary jaws by rotating the screw-threaded spindles 35 in the proper direction. Each of these spindles is provided with a handle 38, by which it may be grasped.

The jaws of the clamping frames are each

of a height that is substantially less than 65 the height of the walls of the said frames, the lower edges of the said jaws being flush with the lower edges of the said frames, as clearly appears from Figs. 2 and 6 of the drawings. Above the jaws each frame is divided by a 70 longitudinal partition 39 and a transverse partition 40 into four equal sections, into each of which fits, as will hereinafter appear, a paste-board cube 41, that is to receive the finished product (Fig. 6). The 75 clamping frames rest on upwardly projecting ledges 25' on the plate member 25.

The plate member 25 and the clamping frames resting thereon may be raised from the ledges 24 into contact with the hopper 80 by a suitable mechanism, including in the case illustrated in the drawings a shaft 42, that is oscillatably mounted in hanger bearing 42', depending from the hopper. To the shaft 42 are fixedly attached cams 43 and a 85 crank 44. Hooks 45 pivoted to the hopper and in engagement with pins 46 on the plate member 25 serve for detachably fastening the plate member 25 with the clamping frames thereon to the hopper (Figs. 2 90 and 4.)

The operation of this device is as follows:—The pointed pins are placed loosely in upright positions into the compartments of the hopper with their blunt ends resting 95 on the hopper bottom. The clamping frames, with their jaws in open position, are placed upon the plate member 25, and the latter raised by the cams 43 by shifting the crank 44 in the proper direction. The 100 hooks 45 are then engaged with the pins 46, to fix the clamping frames and plate member to the hopper. The crank 23 is then turned in the direction of the arrow shown in Fig. 3 of the drawings, whereby a vibrating or reciprocating motion is imparted to the hopper and the elements fixed thereto. By this vibrating motion, pins are caused to pass into the apertures 18 in the hopper bottom, said pins resting with their blunt 110 ends on the plate member 25 between sets of stationary and movable jaws on the clamping frames. It is to be observed that into each aperture 18 only one pin is admitted, those remaining in the compartments of 115 the hopper not interfering with those resting on the plate member 25. After the hopper has been vibrated for the required time, the screw-threaded spindles 35 on the clamping frames are turned clockwise, whereby 120 the movable jaws are shifted toward the stationary jaws into gripping positions, thereby clamping the pins to the frames 26.

In order to allow the clamping frames to be removed from the apparatus, it becomes 125 necessary to lower the same together with the plate member 25. For this purpose the hooks 45 are first disengaged from the pins

46 and then the crank 44 shifted in the direction of the arrow shown in Fig. 4 of the drawings. When the clamping frames are in their lower positions, the pointed ends of 5 the pins clamped thereto clear the hopper bottom.

The clamping frames are then one after 10 the other removed from the apparatus, and the blunt ends of the pins, which project below the said frames, dipped into a, preferably, quick-setting vitreous mass, whereby 15 heads are formed thereon.

The finished product is then mounted upon cubes 41, by forcing a cube into each frame 20 section, limited by the partitions 39 and 40, whereby the points of the pins pierce the cubes, extending into the said cubes as far as the jaws on the frames permit (Fig. 6). After the pins are thus fixed in place, the 25 movable clamping jaws are caused to recede from the stationary jaws, by turning the spindles 35 in the proper direction, so that the pins may be withdrawn from the frames by lifting the cubes, the heads of the pins 30 passing between the jaws, which are, in their open positions, disposed at a distance from each other that is somewhat larger than the heads of the pins. After having been 35 disengaged from the frames, the pins are forced into the cubes throughout their lengths by placing the said pins on a table or similar support, and pressing the cubes downward toward the said support. After one face of a cube has been finished, the operation now described is repeated with the next face thereof, and so on.

It is to be observed that the blunt ends 40 of the pins, before being clamped to the frames, are kept by the plate member 25 in the same plane regardless of the lengths 45 of the pins. In this manner, when the pins are being dipped, they will each receive a head of the same size.

Attention is also called to the fact that 50 the pins are each of a length that they remain, during the vibrating motion of the hopper and frames, partly in the apertures in the hopper bottom. For this reason a single pin only can be fed through each aperture.

55 It is obvious that, while herein the apparatus has been described as containing a specific number of compartments in the hopper and each compartment having a specified number of apertures in its bottom portion, any other suitable arrangement may be made without departing from the invention, which lies mainly in the provision of a pin distributing hopper, in combination with a clamping frame, that so holds the pins that 60 their blunt ends are adapted to be dipped for the purpose specified.

It is to be noted also that, while herein a particular means has been described for imparting a vibrating or reciprocating motion

to the hopper and the elements fixed thereto, and a specific means has been disclosed for clamping the distributed pins to a frame, any other construction may be used within the scope of the appended claims.

What I claim is:—

1. In an apparatus of the character described, the combination with a hopper into which the pins are placed divided into a plurality of compartments each of which is provided with apertures in its bottom portion, of a frame supported by said hopper in a plane below the same, a stationary set of jaws carried by said frame, a movable set of jaws adapted to contact with said stationary set of jaws substantially in the plane 75 of rows of apertures in the hopper bottom, means for shifting said movable set of jaws relative to said stationary set of jaws, and means for imparting a vibrating motion to said hopper and the frame carried thereby. 80

2. In an apparatus according to claim 1, said frame being detachable from said hopper.

3. In an apparatus according to claim 1, said jaws being each of a height that is less 90 than the height of said frame.

4. In an apparatus of the character described, the combination with a hopper into which the pins are placed divided into a plurality of compartments each of which is 95 provided with apertures in its bottom portion, of a frame detachably carried by said hopper in a plane below the same, a stationary set of jaws carried by said frame, a movable set of jaws adapted to contact 100 with said stationary set of jaws substantially in the plane of rows of apertures in the hopper bottom, means for shifting said movable set of jaws relative to said stationary set of jaws, and means for imparting a vi- 105 brating motion to said hopper and the frame carried thereby, said jaws being each of a height that is less than the height of said frame.

5. In an apparatus according to claim 1, 110 said frame being of a height that is substantially less than that of the pins operated upon.

6. In an apparatus according to claim 1, 115 said frame being of a height that is substantially less than that of the pins operated upon, said jaws being each of a height that is less than the height of said frame.

7. An apparatus according to claim 1, 120 comprising means for holding the blunt ends of the pins, before being clamped to said frame, in the same plane regardless of the lengths of the pins.

8. An apparatus according to claim 1, 125 comprising a plate below said frame for holding the blunt ends of the pins, before being clamped to said frame, in the same plane regardless of the lengths of the pins.

- 42
9. In an apparatus according to claim 1, said frame being of a height that the pins remain during the vibrating motion partly in the apertures in the hopper bottom.
  10. An apparatus according to claim 1, comprising means for holding during the vibrating motion the pins partly in said hopper.

11. An apparatus according to claim 1, comprising means for preventing from passing more than one pin at a time through an aperture in the hopper bottom.

Signed at New York, in the county of New York, and State of New York, this 7th day of April, A. D. 1919.

MAXWELL VIDAVER.
